UNITED STATES PATENT OFFICE.

JOHN R. JOHNSON, OF PORTLAND, OREGON.

CROSSING SIGNAL FOR RAILROADS.

Application filed October 11, 1921. Serial No. 507,079.

To all whom it may concern:

Be it known that I, JOHN R. JOHNSON, a citizen of Finland, residing at Portland, in the county of Multnomah and State of Oregon, have invented certain new and useful Improvements in Crossing Signals for Railroads, of which the following is a specification.

This invention relates to improvements in railroad crossing signals and more particularly to an improved structure adapted to be operated by the wheels of the train when the latter passes over the railroad track so that the signal adjacent the crossing will be operated to indicate to the persons approaching the track that a train is approaching the crossing.

Other objects of the invention will appear upon consideration of the following detail description and accompanying drawings, wherein:

The figure illustrates a perspective view of the apparatus constructed in accordance with my invention.

25 Mounted upon the railroad tie 1 adjacent the railway rails 2 is a supporting bar 3 which is rigidly secured to the ties and which has its central portion provided with a bearing 4 to receive an operating shaft 5. This shaft, as shown, extends beneath the rail 2 and is provided with an operating arm 6 adjacent the inner side of the rail 2. A trip wheel 7 is mounted upon the free end of the arm 6 and the arm is long enough to cause the wheel 7 to be disposed adjacent the inner side of the head of the rail so that the wheels of the train passing along the track will engage the trip wheel 7 and cause the trip arm 6 to be swung downwardly whereby the operating shaft 5 will be turned. Coil springs 8 are connected to the trip arm 6 and the supporting bar 3 for normally maintaining the trip arm in an upright position whereby the wheel will be disposed slightly 45 above the top of the rail whereby it may be conveniently engaged by the wheels of the train.

50 Mounted at the side of the track is a supporting post 10 having a bearing 11 to receive the outer end of the operating shaft 5. Rigidly secured to the outer end of the operating shaft 5 beyond the bearing 11 is a cross arm 12 which is keyed or otherwise rigidly secured to the shaft 5 and provided with a striker arm 13 extending parallel to the outer end of the operating shaft

5 so that it may engage a swinging arm 14 loosely hung from the outer end of the shaft 5. The arm 14 is adapted to be freely rotated on the shaft 5 so that the member 13 will engage the arm 14 and swing it in one direction when the shaft 5 is turned but will cause the arm 14 to be stationary when the shaft 5 is turned in the opposite direction. A stop arm 15 is employed to engage the lower end of the swinging arm 14 whereby it can move in only one direction. A cable 16 is connected to the lower end of the swinging arm 14 and this cable leads to an operating lever 17 pivotally mounted upon the signal post 18, which of course, will be disposed near the street crossing. The cable 16 may be of any desired length so that the signal post 18 may be disposed at any distance from the tripping apparatus. The cross arms 19 mounted on the upper end of the signal post 18 are pivotally mounted by a pivot member 20 so that the cross arms may swing to attract the attention of persons approaching the railroad crossing. The outer end of the lever 17 is connected by a rod 21 to one of the cross arms 19 and a coil spring 22 is employed to normally maintain the cross arms in a position opposite to that to which they are moved by the rod 21. The other cross arm is also connected by a spring to the supporting post or signal pole 18 and this cross arm is provided with a depending hammer 23 suspended between two metallic plates 24 which are supported by a bracket from the post 18 so that as the cross arms 19 move the member 23 will intermittently strike the plates 24.

55 A bracket arm 25 is employed to connect an operating lever 26 corresponding to the operating lever 17 and a cable 27 is extended from this lever to the signal apparatus at the opposite side of the crossing so that the device may be operated by a train approaching from either direction.

100 When the apparatus is in use, it will be mounted as shown and it will be noted that when the train approaches the wheels will engage the trip wheel 7, the springs 8 causing the wheel to spring back to normal position after each car wheel passes over the trip wheel so that there will be an intermittent movement of the trip wheels while the train is passing over the rails at this point. This will cause an intermittent movement of the operating apparatus so that the cross arms 19 will be rapidly moved

upwardly and downwardly to attract the attention of a person approaching the railroad crossing so that they will be made aware of the approach of the train while the 5 audible signal will attract attention and thus prevent any accident at the crossing.

Minor changes may be made in the details of construction without departing from the spirit of the invention or the scope of the 10 claims hereunto appended.

What is claimed is:—

1. A railroad signal apparatus comprising the combination with railway rails, and a signal including pivotally mounted cross arms, means for holding the cross arms in a fixed position, a trip wheel arranged near one of the rails to be engaged by the wheels of the train, an operating shaft connected to the trip wheels, an operating arm 15 secured to the outer end of the shaft, a swinging lever loosely connected to the said shaft and adapted to be engaged by the operating lever when the latter swings in one direction, means to limit the movement of the swinging arm in the opposite direction, a lever pivotally mounted upon the signal post supporting the cross arm, means connecting the said cross arms with the said lever, and a flexible cable connecting the said 20 swinging arm with the said lever whereby the said swinging signal arms may be intermittently swung as the wheels pass over the said trip wheel, an audible signal and means carried by one of the moving signal arms to strike the audible signal, the said trip wheel being provided with spring means to return the wheel to operative position as each wheel on the train 25 passes over the said trip wheel.
2. A railroad signal apparatus comprising the combination with railway rails, and a signal including pivotally mounted cross arms, means for holding the cross arms in a fixed position, a trip wheel arranged near one of the rails to be engaged by the wheels of the train, an operating shaft connected to the trip wheels, an operating arm secured to the outer end of the shaft, a swinging lever loosely connected to the said shaft and adapted to be engaged by the operating lever when the latter swings in one direction, means to limit the movement of the swinging arm in the opposite direction, a lever pivotally mounted upon the signal post supporting the cross arm, means connecting the said cross arms with the said lever, and a flexible cable connecting the said swinging arm with the said lever whereby the said swinging signal arms may be intermittently swung as the wheels pass over the said trip wheel, an audible signal and means carried by one of the moving signal arms to strike the audible signal, the said trip wheel being provided with spring means to return the wheel to operative position as each wheel on the train passes over the said trip wheel.

2. A railroad signal apparatus comprising the combination with railway rails, and a signal including pivotally mounted cross arms, means for holding the cross arms in a fixed position, a trip wheel arranged near one of the rails to be engaged by the wheels of the train, an operating shaft connected to the trip wheels, an operating arm secured to the outer end of the shaft, a swinging lever loosely connected to the said shaft and adapted to be engaged by the operating lever when the latter swings in one direction, means to limit the movement of the swinging arm in the opposite direction, a lever pivotally mounted upon the signal post supporting the cross arm, means connecting the said cross arms with the said lever, and a flexible cable connecting the said swinging arm with the said lever whereby the said swinging signal arms may be intermittently swung as the wheels pass over the said trip wheel, an audible signal and means carried by one of the moving signal arms to strike the audible signal, the said trip wheel being provided with spring means to return the wheel to operative position as each wheel on the train passes over the said trip wheel.
